Claims priority, application Germany October 27, 1957

15 Claims. (Cl. 197—66)

The present invention relates to a device for line spacing power-operated typewriters and similar office machines having an electrically driven carriage return mechanism.

It has been proposed to employ an electrically operated carriage return mechanism as the drive means for the line spacing operation, whereby this line spacing operation is performed either independently of a carriage return movement or followed by a subsequent carriage return upon actuation of separate keys.

This mechanism may be used as the line spacing apparatus in either fully or partially electrically-operated machines. In both types of machines, a line spacing key which is adapted to trigger the line spacing operation independently of the carriage return step also serves to actuate a mechanical locking device which is utilized for locking the carriage return mechanism when said key is depressed. However, the electric control mechanisms in these two types of machines differ from one another. In semielectric machines, two relays controlling an electric circuit are employed for coupling the carriage return device to a motor through the intermediary of a magnetic clutch disposed in said circuit. These relays are actuated by means of pairs of shunted contact elements provided for the line spacing key and the carriage return key, respectively.

In contradistinction, completely electrically operated machines employ only one relay provided with a pair of holding contacts. This relay can only be energized by actuation of the carriage return key, whereupon a pair of operating contacts for this same relay serves to close the electric circuit for the magnetic clutch. A switch is connected in parallel to this pair of operating contacts, said switch being adapted to be closed only by the line spacing key, whereby the circuit of the magnetic clutch is directly closed independently of the relay.

Consequently, separate electric circuits had to be provided for the carriage return and the line spacing. In addition to this, it was difficult to obtain a precise operation of the successive steps of this device. For example, occasionally, the line spacing was interrupted upon premature release of the respective control key prior to completion of the switching steps.

It is, therefore, an object of the present invention to provide improved means for line spacing a machine adapted to operate independently of, or immediately before, a subsequent carriage return operation.

It is another object of the invention to provide a new and improved carriage return operation and the electric circuit controlling the same.

It is a further object of the present invention to provide a common electrical circuit for initiating a line spacing operation independent of a carriage return movement in response to depression of a line spacing key, and for initiating line spacing operations with subsequent carriage return movement in response to depression of a carriage return key.

It is a still further object of the invention to provide

means adapted to complete the line spacing step independently of the release of a depressed key.

It is a further object of the invention to provide means to lock the carriage until the line spacing step is completed irrespective of releasing of the key prior to completion of the line spacing step.

It is an additional object of the invention to provide means controlling the rate of energization of a relay to enable the line spacing mechanism to adequately prepare for a subsequent line spacing operation.

Still further objects and the entire scope of applicability of the present invention will become apparent from the detailed description given hereinafter; it should be understood, however, that the detailed description and specific examples, while indicating preferred embodiments of the invention, are given by way of illustration only, since various changes and modifications within the spirit and scope of the invention will become apparent to those skilled in the art from this detailed description.

In the drawings:

Figure 1 illustrates schematically a perspective view of a carriage return mechanism and line spacing device according to the present invention;

Figure 2 shows diagrammatically the electric control circuit for the mechanism and device illustrated in Figure 1.

Figure 3 is a fragmentary front view showing in detail the construction of the carriage locking lever and its associated upright lever forming part of the carriage locking mechanism, pursuant to the present invention;

Figure 4 is a sectional view taken along line IV—IV of Figure 3, showing the connection between a control lever and its associated upright lever.

General description

The present invention may be embodied in typewriters or like machines of various types. For the purpose of illustration, the invention is shown in an electrically-operated typewriter. The drawings illustrate only enough of the typewriter structure to assist in illustrating and explaining the manner in which the device may be successfully used in an electric typewriter.

Referring now in detail to the drawings and, more particularly, to Figure 1, there is shown a magnetic clutch 1 adapted to positively couple a drawband reel 2 to rotatable shaft 3a driven by a continuously running electric motor 36. A drawband 4, wound about and carried by the reel 2, is guided by means of grooved pulleys 5 and 5a, said band being looped at one end and secured to a pin 7 supported by a leg 7a of a line spacing lever 8. This lever 8 serves to effectuate the line spacing operation which moves a work sheet to a new position for further typing, as will be more fully described hereinafter. A rack 12a, provided with a plurality of teeth 12b, is operatively connected to a typewriter carriage 12 (only partially shown), said rack meshing with the teeth of a pinion 13 supported on a rotatable shaft 15.

A ratchet wheel 14 provided with gear teeth 14a is also carried by the shaft 15. A locking pawl 6a disposed adjacent the ratchet wheel 14 and adapted to engage the teeth 14a serves as the forward end of a locking lever 6 which rocks about a pivot bolt or shaft 16. The line-spacing lever 8 is constructed in the form of a bell crank and is provided with an arm 8a supporting a line-spacing pawl 9. A tension spring 10 carried by the carriage 12 has one end fastened to the arm 8a to normally maintain said arm and its associated pawl 9 in its disengaged or inoperative position. A line-spacing ratchet wheel 11 secured to a typewriter platen (not shown) initiates incremental line spacing of a work sheet upon engagement of the line-spacing pawl 9 with the teeth of the ratchet

wheel 11. Thus, upon actuation of the line-spacing lever 8, the pawl 9, by means of a drawband 4, engages the ratchet wheel 11 and causes a line-spacing operation. Additionally, there is provided a shield 10a, carried by the carriage 12, serving to hold and maintain the pawl 9 out of engagement with the ratchet wheel 11.

During the actual typing operation, the advancing movement of the carriage is obtained by means of a carriage advancing ribbon or tape 17, wound about a grooved drum 17a, supported on a shaft 17b. A spring 18, disposed centrally of said drum, is in registry with one end of said tape to cause the latter to wind about the drum 17a. The above-described advancing mechanism is conventionally employed in typewriters.

In accordance with the present invention, the locking device for locking the carriage to prevent the return movement of the same during a line spacing operation, is mechanically actuated by a key Z. The key Z is mounted on an arm 61 oscillating about a shaft 62 and constituting one of a plurality of typewriter keys forming the typewriter keyboard (not shown); said key also serving to actuate a double-throw contact switch z₁, as best seen in Figure 2. A link 60 is connected at one end to the arm 61 and at its opposite end is secured to one leg 63a of a right-angle lever 63 which is pivotally supported on a shaft 64. The other leg 63b of lever 63 is secured to a pull rod 19 which, in turn, has its opposite end flexed into a hook 69 receivable in an aperture 65, provided in an actuator or control lever 20. This last-mentioned lever is supported by an angle bracket 66 and is pivotable about a stub shaft 21 mounted on said bracket.

The left-hand portion of the control lever 20 is slightly flexed and its left end is provided with an extension defining a trip nose 22 actuated by means of the pull rod 19. The opposite end of said control lever 20 is slightly inclined and has its end portion secured to a substantially upright lever 23 by means of an oblong-shaped pin slot 22a (see Figure 4). The lever 23 is pivotally mounted adjacent its upper end on a shaft 24 supported by a bracket 24a (see Figure 3). The uppermost portion of the lever 23 is provided with a lateral stop flange 23a adapted to normally abut against the top surface of the locking lever 6 pivoted at 16 on the lever 23. The locking pawl 6a is engageable with the ratchet wheel 14 for the purpose of locking the carriage 12 to prevent movement thereof. The locking lever 6 is held in a predetermined position against the stop 23a by means of a spring 26 carried by a bracket 26a, said spring exerting an upwardly directed biasing force on the bottom surface of the locking lever 6 through the intermediary of a pin 25 located above the spring 26. It is to be noted that the lever 23 upon actuation of the key Z rotates in a clockwise direction about the axis of shaft 24. Figure 1 discloses the position of lever 23 upon depression of key Z. If the key Z is not actuated, then lever 23 remains in its rest position, whereby the locking pawl 6a does not engage the teeth 14a of the ratchet wheel 14. These aforementioned parts, and more particularly, pawl 6a, serve to lock the ratchet wheel 14, thereby preventing displacement of the carriage 12 during the time the key Z is held in its depressed position.

The elements described hereinafter are utilized as an automatic control for the line spacing mechanism independent of the manual actuation of the key Z. A vertically arranged control or push rod 28 is carried by a stationary bracket 28a and supports a circumferentially arranged spring 29, disposed between upper limit stop 30a and the end 28b of the bracket 28a. The upper limit stop 30a and a lower limit stop 30 are also supported by said push rod. A cushion lever 31 provided with a slot 31c for receiving the upper end of said push rod is mounted at one end thereof and is adjustable along the length of said push rod by means of a set screw 31b permitting adjustment of the width of said slot. The cushion lever 31 is further provided with an upwardly extending

finger 31a defining a holding edge adapted to abut the bottom of the locking lever 6. The lower or bottom end of the push rod 28 is operatively connected to a rocking lever 33 pivoting about a shaft 33b, said bottom end of the push rod being fastened to a cross member 105 slidable in oval-shaped slots 105a provided on said rocking lever with the aid of pin means 106 guided therein. A switch 32 is mounted on a leg 107 which is secured to and extending from the cross member 105, said switch comprising single pole-single throw elements 32a and single pole-double throw elements 32b. The bracket 28a is secured to the typewriter or office machine frame (not shown).

Rocking lever 33 is provided at its free end with a finger 33a extending through and guided by a slot 51b formed in a plate member 51, also secured to the machine frame. The finger 33a rests on a shoulder 34b at the upper end of a holding lever 34 which is pivotally mounted on a shaft 50a supported by said plate member. At the lower end of the holding lever 34, there is provided a downwardly extending arm 34a abutting against a stop member 51a extending from the plate member 51, said arm 34a being biased in one direction by a spring 50. One end of a spring 52 is attached to the plate 51, while its other end is secured to the left-hand portion of the control lever 20, so as to pull the latter in the direction of said plate member. This mechanism is used for the continuous and exact incremental spacing of the work sheet to the next desired line when the key Z is depressed. The operation thereof will be more fully described later on.

Referring now to Figure 2, the motor 36 is connected to an A.C. power line 37a by means of a double pole-single throw switch 37 and a single pole-double throw switch 38. The motor 36 is operatively connected to the drawband reel 2, carrying the drawband 4 when an electric coil of the magnetic clutch 1 is energized by an electric current (see Figure 1). A rectifier 39, in circuit with said motor and receiving its current from said A.C. power line 37a via transformer 40, supplies D.C. current for the purpose of energizing the electromagnetic clutch 1 and other components constituting the electric circuits, as will be more fully described hereinafter. One terminal of the clutch 1 will be connected to the plus terminal of the rectifier 39 via a switch r₃ when moved to its lower position by means of a main relay R, whereby this switch r₃ engages contact point 204. The main relay R operates four switches r₁, r₂, r₃ and r₄. The other terminal of said clutch is connected to the minus terminal of said rectifier via junction 208. One terminal of the relay R is directly connected to the minus terminal of the rectifier 39 via junction 207, while the other terminal thereof is connected to the positive terminal of said rectifier by means of a rheostat 41, the single pole-single throw switch 32a and switches 42, 43 and 44. The switch 42 is actuated by a correcting space bar; the switch 43 is a limit switch, while the switch 44 is a tabulator switch. A capacitor 45 has one terminal connected to the plus terminal of the rectifier 39 by means of switches z₁, 32b, 42, 43 and 44, the opposite terminal of said capacitor being connected to the minus terminal of said rectifier via switch r₂ when the relay is deenergized and said switch engages point 201.

A resistor 46 is connected in series to the capacitor 45 upon closing of a contact switch w₁, said contact switch being operated by a key W which also actuates switches z₁ and w₂. A resistor 47 will be shunted to the capacitor 45 when the switch z₁ is moved to its lower position engaging contact point 209, thereby energizing the coil of the relay R, actuating said relay and causing switch r₂ to engage point 202. When the relay switch r₁ engages point 200, it connects one terminal of the coil of the relay R to the plus terminal of the rectifier 39, thereby closing the circuit through said relay coil. The contact switch w₂ which is closed upon actuation of the key W

is adapted to complete a circuit through magnet 48, which circuit is supplied from the rectifier 39 when the switch r_4 is engaging point 205. The magnet 48 serves to unlock the keyboard of the typewriter when the main circuit breaker switch 37 and switch 49 are closed. Upon opening of the switch 49, the keyboard is locked, unless the switch w_2 is closed.

The switch 32 including switching elements 32a and 32b is schematically illustrated in Figure 2. The mechanism placing the ratchet wheel 14 in registry with the switch 32 is schematically illustrated in Figure 2. This mechanism includes the locking lever 6 and the push rod 28 with the cushion lever 31 mounted thereon. The line spacing operation is controlled by the line spacing lever 8 which, upon energization of the magnetic clutch 1, is actuated via the drawband 4, said drawband 4 being instantaneously tensioned under the action transmitted by said clutch. The line spacing pawl 9 engages the teeth of ratchet wheel 11, causing rotation of said wheel. The drawband 4 is also adapted to exert a force pulling the carriage 12. This movement can be retarded by the inertia of said carriage when at rest, i.e., when the line spacing operation is followed by a carriage return step. If the line spacing operation shall take place without carriage return, the locking lever 6 locks the carriage 12 when the pawl 6a engages the ratchet wheel 14, thereby preventing any movement of the gear 13 and its associated rack 12a in registry with the carriage 12.

Line spacing without carriage return

The actuation of the locking means for preventing motion of the carriage 12 and the energization of the relay R are initiated by the key Z. Upon depression of said key Z, its motion is transmitted by the pull rod 19 to the pivotally mounted control lever 20, thereby rocking the upright lever 23 about the pivot shaft 24 in a clockwise direction, the bottom portion of the lever 23 moving in the direction of the arrow 23b. As a result of this pivotal movement of the lever 23 about the shaft 24 in a clockwise direction, the locking lever 6 is moved in the direction of the wheel 14, whereby the locking pawl 6a is brought into contact with the teeth 14a of said wheel. At the same time, the spring 26 holds the pin 25 in its resting position, so that the left end of the locking lever 6 abuts the stop flange 23a. During the last phase of this locking step, the trip nose 22 releases the holding lever 34 which previously was locked, as its arm 34a was abutting the stop 51a under the action of the spring member 50. Upon release of the holding lever 34, the rocking lever 33 is also released since its finger 33a no longer maintains its abutting relationship with the shoulder 34b provided on said holding lever. As a result of this, the push rod 28 moves upwardly under the action of the spring 29, said movement being limited by the stop 30. Thus, the cushion lever 31 is brought into a new position directly below the locking lever 6. The single pole switch element 32a, disposed adjacent the lower end of the push rod 28, is adjusted and positioned in such a manner, that said switch 32a does not close until the cushion lever 31 has arrived in exactly the position described above. The position of the double-throw switch 32b has now changed, whereby said switch engages contact point 210, see Figure 2. Furthermore, the holding surface or upper edge 31a of the cushion lever 31 contacts the lower surface of the locking lever 6 in such a manner, that the locking pawl 6a engages one of the teeth 14a of ratchet wheel 14 to maintain the carriage in its locked position even if the key Z is subsequently released.

The importance of the operation and function of the cushion lever 31 can best be appreciated if it is considered that said holding surface prevents a counter-clockwise pivotal movement of the lever 23 about the shaft 24. This pivotal movement would normally occur

upon release of the key Z as a result of the pulling force exerted by the return spring 52 acting on the control lever 20. Prior to depression of the key Z, i.e., when the switch z_1 contacts point 211, the capacitor is connected directly across the rectifier 39 to permit charging of said capacitor. Thus, upon depression of key Z, the contact switch z_1 moves down to a new position 209 and connects said capacitor to line junction 63, as illustrated in Figure 2.

- 10 When the contact 32a is closed, due to the lifting of the push rod 28, as previously described, the capacitor 45 will be shunted to the coil of the relay R. Consequently, the coil of the relay R and the shunted capacitor 45 are connected to the rectifier 39 via the rheostat 41 and switches 32a, 42, 43 and 44. Thus, the coil of the relay R, which is fed directly by the rectifier, will be energized to activate switches r_1 , r_2 , r_3 and r_4 . Closing of the switch r_3 , by moving it into position 204, connects the magnetic clutch 1 to the rectifier 39 and energizes said clutch. Due to the energization of the clutch 1, torque will be transmitted to the drum 2, causing tensioning of the drawband 4 and, thereby, engagement of the line spacing pawl 9 with its associated ratchet wheel 11, thus carrying out a line spacing operation on a work sheet. After completion of the line spacing step, the pulling force exerted by said drawband and transmitted to the carriage 12 by an elbow 5b is increased, due to the torque build-up of said clutch. This pulling force is transmitted to the teeth 14a of the ratchet wheel 14 by means of rack 12a and pinion 13, turning the locking lever 6 about its fulcrum or pivot 16 in a counterclockwise direction, overcoming the force of the spring 26.
- 35 As a result of this, the push rod 28 is moved downwardly, whereupon the switch element 32a of the switch 32 opens, deenergizing the coil of the relay R and causing the clutch 1 to disengage the drum 2 from the driving motor 36. The relay switch r_3 then assumes its initial contact position 203. Since the clutch 1 is now 40 disengaged, the pulling force previously exerted on the line spacing lever 8 through the intermediary of drawband 4 is entirely removed and the lever 8 will return to its initial position under the action of the spring 10. If the key Z would be released prior to the operational 45 steps described above, the spring 52 would pull the control lever 20 into its neutral or rest position and the locking lever 6 would return to its original position against the action of the spring 26, while the clutch 1 would become disengaged. Thus, the upright lever 23 50 would withdraw the pawl 6a of locking lever 6 from the previously engaged teeth of ratchet wheel 14. Such disengaging movement could not be prevented by the cushion lever 31.

- However, if the key Z is continuously held in its depressed position, one line spacing step will be followed by another, as the control lever 20 will not be able to return to its rest position under the action of the spring 52. Thus, control lever 20 will remain in its carriage locking position, i.e., will be biased in the direction of the arrow 23b. Therefore, after the completion of one line spacing operation, the locking lever 6 will disengage from the ratchet wheel 14, opening contact switch 32a due to a lowering of push rod 28. Consequently, the relay R will be deenergized, as described in the foregoing. However, prior to the deenergization of said relay R, the capacitor 45 has been discharged via the closed switch r_2 , which is in position 202, the resistor 47 and the closed contact z_1 , to dissipate the charge on the capacitor. If, now, the pressure acting on the locking lever 6 is decreased by releasing the tension on the drawband 4, line spacing lever 8 and the rack 12a, the push rod 28 will be moved upwardly under the action of spring 29, to reclose the switch 32a. This operation 70 occurs at such high velocity that the lever 8 is unable

to return to its initial position under the action of spring 10, so as to be in its proper position for a subsequent line spacing step. In order to obtain an accurate and properly functioning line spacing operation, the reclosing step of the switch 32a must be delayed long enough to enable the line spacing lever 8 to return to its initial position and to initiate another line spacing operation.

This required time-delay in the function of the relay R is obtained by the resistor 41. During the first line spacing step, the capacitor 45 is completely charged when shunted across the relay R. When the switch 32a is now reclosed, the capacitor 45 will be partially discharged and the rheostat 41 together with the capacitor 45 form a time-delay RC member. As a result of this, the subsequent energization of relay R is delayed for a predetermined increment of time, said delay being of such magnitude that the spring 10 has sufficient time to return the line spacing lever 8 to its initial position, thus permitting the next line spacing operation. Consequently, one properly timed line spacing cycle is followed by another as long as the key Z is held in its depressed position. By changing the values of the time delay RC member, the number of line spacing steps per unit of time may be increased or decreased as desired. Such change can be obtained, for example, by connecting additional resistances to the rheostat 41 or by varying said rheostat.

The carriage return

The essential circuit components for performing the line spacing operation without carriage return movement are also employed for carrying out a line spacing operation with subsequent carriage return. Thus, upon depression of the key W, the contact switches z₁, w₁ and w₂ are closed. However, the locking device for the carriage 12, including the locking lever 6 and ratchet wheel 14 are not in their locking positions, as described above, since the key W does not actuate the pull rod 19 and its associated members. The capacitor 45, which was in charged condition prior to depression of the key W and connected in the circuit of rectifier 39 via components r₂, z₁, 32b, 42, 43 and 44, now discharges via the contact z₁ in position 209, and the coil of the relay R. As a result thereof, the relay coil is energized and actuates switches r₁, r₂, r₃ and r₄, said switches assuming a new position. More specifically, the relay switch r₁ assumes the position 200, thereby maintaining said relay continually energized via elements r₁, 32b, 42, 43 and 44, even if the capacitor 45 is discharged. The relay switch r₃ then also closed, i.e., in position 204, connects the magnetic clutch 1 directly to the rectifier 39, whereby current is fed to clutch 1 until the limit switch 43 opens to interrupt the current supply to the coil of the relay R, thus deenergizing the latter.

Upon energization of clutch 1, the line spacing operation will be carried out by means of the line spacing pawl 9 engaging the ratchet wheel 11. In addition, carriage return is obtained, as the ratchet wheel 14 is not in its locked position. However, it may be that the key W is still depressed when the limit switch 43 has opened and reclosed after an immediate return of the carriage. Such immediate reclosing could cause recharging of the capacitor 45. To prevent such premature charging, the resistor 47 is shunted to the capacitor 45 as long as the relay R is energized. Thus, the capacitor 45 will completely discharge during energization of the relay R and the high resistance 46 prevents recharging of the capacitor. Upon release of the key W, the contact switch z₁ resumes its initial position 211 and again connects the capacitor 45 to the rectifier 39, so as to charge the capacitor. The release of the key W simultaneously causes the switch w₁ to open and to disconnect the capacitor 45 from the relay R.

Locking

The magnet 48 acts on a known ball locking device 75

(not shown) adapted to lock the typewriter keyboard including the keys W and Z. Upon closing of the single throw switch 37, having switching elements 37b and 37c, the magnet unlocks the keyboard to put the typewriter in operation. The contact switch r₄ of the relay R and the contact switch 49 of the margin set key are adapted to open the circuit of the magnet 48, so that the keyboard can be locked. Upon actuation of the margin set key, the contact 49 can be reclosed, thus unlocking the keyboard. When the contact 49 is opened, a line spacing operation with a subsequent carriage return can be carried out, because the key W acts on the contact w₂ which is below the key Z. This contact w₂ closes the circuit of the magnet 48 to unlock the keyboard. Accordingly, the locking of the keyboard is released upon a slight pressure on the key W. When the relay R is energized, the contact r₄ moves to the position 206 and thereby opens the circuit of the magnet 48. Thus, the keyboard becomes locked during the carriage return. The line spacing and the carriage return steps can be interrupted by actuation of the switches 42, 43 or 44, which are inserted in series in the control circuit for the relay R. Such interruption may be carried out during tabulation or upon depressing the back-spacer.

Thus, the same relay R is used for actuating the line spacing step with or without subsequent carriage return. For line spacing without subsequent carriage return, the circuit of the relay R will be closed by the contact 32a of the switch 32, when released by the pull rod 28.

When the line spacing step is carried out by depressing the key W, the contacts w₁ and w₂ close, while the locking device remains in its rest position. The capacitor 45 discharges, as described in the foregoing, through the coil of the relay R. The relay R is energized and remains energized via the holding switch r₁. This self-holding function of the relay R is very important for the line spacing step with subsequent carriage return. However, the self-holding means must be rendered ineffective for the line spacing step without subsequent carriage return, because an active self-holding means would prevent opening of the contact 32a carried out by means of the pull rod 28. Therefore, the contact 32b is provided to close the circuit for the self-holding means in either of its two resting positions 210 or 212. However, shortly after the mechanism for the line spacing step is disconnected by the contact 32a of the switch 32, the contact 32b changes its position from 212 to 210 or versa, thereby rendering the controlling energizing circuit for the relay R entirely deenergized for a short period of time and causing opening of the relay R, as the latter has a very short release time.

I claim:

1. In a power-operated typewriter and the like, a displaceable carriage, a platen rotatably mounted on said carriage, line spacing means connected to said platen for rotating said platen in predetermined increments, drive means communicating with said line spacing means and said carriage and adapted to initiate at least one line spacing operation on a work sheet, locking means operatively connected to said carriage and adapted to lock said carriage to prevent movement thereof, first key means in registry with said carriage locking means for actuating the latter, control means actuated by said first key means for operating said drive means including an electrical power source, a relay, first switch means operated by said first key means to connect said relay to said power source, and second switch means actuated by said relay for connecting said drive means to said power source, second key means for actuating said control means independently of said first key means, whereby said drive means performs a line spacing operation on said work sheet followed by a carriage displacement, and means communicating with said locking means and said first switch means, said communicating means being actuated upon by said drive means via said locking means

for operating said first switch means upon completion of a line spacing operation, said control means further including time delay means operatively connected to said relay to prevent premature energization thereof and to permit said line spacing means to return to a predetermined initial position in readiness for a subsequent line spacing operation.

2. A power-operated typewriter and the like according to claim 1, wherein said communicating means include a push rod, a biasing spring carried by said rod, a cushion lever supported at one end of said rod and adapted to contact said locking means, said biasing spring moving said push rod in one direction to close said first switch means when said drive means is inoperative.

3. A power-operated typewriter and the like, according to claim 2, wherein said communicating means further include a rocking lever connected to the other end of said push rod, said rocking lever being provided with an extension defining a finger, a holding lever pivotably connected to said first key means and in one position abutting said finger, whereby actuation of said first key means pivoting said holding lever will release said finger to permit displacement of said push rod for intermittent actuation of said first switch means.

4. In a power-operated typewriter and the like, a displaceable carriage, a platen rotatably mounted on said carriage, line spacing means connected to said platen for rotating said platen in predetermined increments, drive means communicating with said line spacing means and said carriage and adapted to initiate at least one line spacing operation on a work sheet, locking means operatively connected to said carriage and adapted to lock said carriage to prevent movement thereof, first key means in registry with said carriage locking means for actuating the latter, control means actuated by said first key means for operating said drive means including an electrical power source, a relay, first switch means operated by said first key means to connect said relay to said power source, and second switch means actuated by said relay for connecting said drive means to said power source, and second key means for actuating said control means independently of said first key means, said control means further including a capacitor supplying electric energy to said relay upon actuation of said second key means, said energizing relay connecting said drive means to said power source via the intermediary of said second switch means, said locking means remaining inoperative during actuation of said second key means, whereby said drive means causes a line spacing operation which is followed by a carriage displacement.

5. A power-operated typewriter and the like according to claim 4, wherein said control means further includes a resistor which is shunted to said capacitor during energization of said relay.

6. A device for line spacing typewriters and similar office machines provided with a displaceable carriage comprising driving means in registry with said carriage for driving the latter, relay means in an electric circuit with and controlling said driving means, first key means for initially energizing said relay means, a line spacing mechanism actuated by said driving means and com-

municating with said carriage, a ratchet wheel associated with said carriage, a locking lever engageable with said ratchet wheel in one position to lock said carriage, a first switch actuated by said first key means and controlling

5 said relay means, a push rod for engaging said locking lever and said first switch, a holding device operatively connected to said push rod and adapted to release said push rod for engaging movement thereof upon actuation of said first key means, second switch means actuated by 10 said relay means and connecting said drive means to a power source and a second key controlling said relay means independently of said push rod and said locking lever.

7. The device according to claim 6, including a capacitor adapted to be connected in circuit with said relay means by said first key means, and a resistor adapted to be connected in series with said capacitor and said relay means upon actuation of said first key means.

8. The device according to claim 7, wherein the magnitude of the resistance in said circuit is variable so that the product of the capacitance of said capacitor and the resistance of said resistor can be altered, thereby defining an adjustable time delay component.

9. The device according to claim 6, wherein a plurality of switches are connected in series to and control said relay means, said switches including a limit switch and a tabulator switch.

10. The device according to claim 6, including magnet means for locking the keyboard of said typewriter 25 upon depression of said second key, whereby said keyboard is locked during displacement of said carriage.

11. The device according to claim 6, wherein said holding device comprises a pivotal holding lever responsive to actuation of said first key means, a control lever 30 abutting one arm of said holding lever and a rocking lever held in a predetermined position by said holding lever and released therefrom upon actuation of said first key means.

12. The device according to claim 11, wherein said push rod is carried by said rocking lever and is adapted 35 to control engagement of said locking lever with said ratchet wheel upon actuation of said first key means.

13. The device according to claim 11, including a cushion lever supported at one end of said push rod and 40 engageable in one position with said locking lever.

14. The device according to claim 6, including spring means disposed adjacent said locking lever and influencing the engagement of said locking lever with said ratchet wheel.

15. The device according to claim 6, including biasing means carried by said push rod urging said rod into engagement with said locking lever upon actuation of said first key means.
